UNITED STATES PATENT OFFICE.

ARTHUR MARTIN, OF PARIS, FRANCE, ASSIGNOR TO JOSEPH WILD & CO.,
OF NEW YORK, N. Y.

DESIGN FOR CARPETS.

Specification forming part of Design No. **6,261**, dated November 19, 1872.

To all whom it may concern:

Be it known that I, ARTHUR MARTIN, of Paris, in France, have invented a new and original Design for a Carpet, of which the following is a specification:

The accompanying photograph fully illustrates my invention.

This invention relates to a new carpet design, which, by a simple arrangement of parts, produces a rich and variegated appearance. Every main subdivision of the design, of which but a portion is shown on the photograph, has a center of elongated hexagonal form, around which are grouped four larger figures, consti-

tuting the broad border to the hexagon. At the ends of the latter start two large diamond-shaped figures, which wedge between the aforementioned border figures, as shown. All the parts and figures herein referred to contain ornamental scrolls and devices, which are clearly represented in the photograph.

I claim as my invention—

The design for a carpet, as shown.

ARTHUR MARTIN.
